JAMES A. CAMERON, OF BROOKLYN, NEW YORK, ASSIGNOR TO CAMERON MACHINE COMPANY, OF BROOKLYN, NEW YORK, A CORPORATION OF NEW YORK

COUNTERWEIGHTING DEVICE FOR WINDING MACHINES

Application filed October 18, 1928. Serial No. 313,277.

This invention relates to winding machines for webs of flexible material, and has for its main object the production of means whereby coils of flexible material may be so wound as to have such different characteristics of hardness as may be desired under different conditions or with different materials.

In an application filed July 28, 1926, Ser. No. 125,350, now Patent 1,707,047, March 26, 1929, is disclosed a winding machine in which a member, displaceable by the accumulation of wound material, is provided with a counterweighting device consisting of a plurality of weights flexibly carried as by a sprocket chain that passes over a sprocket. The main feature of this invention is to provide means whereby the same end may be accomplished by a weight carried by a rigid arm.

20 In the accompanying drawings the invention is disclosed in a concrete and preferred form in which:

Fig. 1 is a view partly in side elevation and partly in section, of a machine embodying the 25 invention;

Fig. 2 is a view looking in the direction of arrow 2 of Fig. 1, partly in elevation and partly in section;

Fig. 3 is a view in elevation of the upper 30 part of Fig. 1 showing the parts adjusted to a different position; and

Fig. 4 is a sectional detail view substantially on the plane of line 4—4 of Fig. 1.

The character of the winding machine may 35 vary widely, but, in the present instance, the winding means comprise two drums 1 and 2. 3 indicates slitting means which may or may not be employed. The member to be counterweighted and which is displaceable by accumulation of wound material may be either a winding shaft or a top pressure roll. In the present instance, 4 is a winding shaft and 5 is a top pressure roll, and the invention can be adequately explained by assuming that 40 the top pressure roll is the displaceable member to be counterweighted.

6 indicates a pivotally supported arm that turns in response to the displacement of a member such as 5, and 7 is a weight mounted 45 on the arm, said weight moving lengthwise of

the arm in response to the turning movement of the arm.

The particular means for effecting these movements may, of course, vary widely but in the present case they are constructed as 55 follows:

Displaceable member 5 is supported by a carriage 8 that slides on guides 9 of the framework. 10 is a sprocket wheel at the upper end of the machine over which passes chain 11 attached at one end to carriage 8 and having at its other end a counterweight 12 sliding on inclined ways 13. Sprocket 10 is carried by shaft 14 which, in turn, supports arm 6. As here shown, the parts are 60 so related that while displaceable member 5 moves from its lowermost position (indicated in full lines in Fig. 1) to its uppermost position (indicated in dotted lines in Fig. 1) arm 6 will move from its full line position at one 65 side of its pivotal axis to the dotted line position at the other side thereof, thus describing approximately one-half of a revolution. 15 is a cam constituting a means for shifting weight 7 lengthwise of arm 6 in response to the turning movement of the latter. It will now be clear that any desired movement of weight 7 may be obtained by having 70 differently shaped cams 15. In the present instance, cam 15 is so shaped that, as arm 6 moves toward the vertical, weight 7 moves 75 toward center 14, and, as arm 6 passes over the vertical and moves downwardly on the other side, weight 7 will be moved outwardly.

The effect of these movements is to decrease 80 the effectiveness of weight 7 as it rises thereby lessening the pressure of member 5 against 4, and to increase its effectiveness on the other side of the center so as to still further lessen the pressure of 5 against 4. Cam 15 may also 85 be adjusted around center 14, which it loosely surrounds, by means of slot 16 and set-screw 17. The effect of an adjustment of this character is indicated in Fig. 3. By substituting different cams or by different adjustments of cam 15, the amplitude of movement of 90 weight 7 can be controlled.

The detail construction of weight 7 is preferably as follows: as shown in Fig. 4, weight 7 is preferably made of two parts 7^a and 7^b 100

spaced apart, and between which are anti-friction rollers 18 that ride on arm 6 which latter extends between 7^a and 7^b. Part 7^a carries a cam roller 19 that engages in cam 15.

5 Preferably, and as shown in Fig. 2, the arrangement of the instrumentalities is in duplicate, there being a train of connections at each side of the machine.

I claim:

10 1. In a winding machine, a member upwardly displaceable by accumulation of wound material, and counterweighting means for said member including: a pivoted arm, means to turn said arm on its pivot in response to the displacement of the member, a weight on the arm, and means to move the weight lengthwise of the arm in response to the turning movement of the arm.

20 2. In a winding machine, a member upwardly displaceable by accumulation of wound material, and counterweighting means for said member including: a pivoted arm, means to turn said arm on its pivot in response to the displacement of the member, a weight on the arm, and means to move the weight in opposite directions lengthwise of the arm in response to the turning movement of the arm.

30 3. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and means to move the weight lengthwise of the arm in response to the turning movement of the arm.

40 4. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and means to move the weight in opposite directions lengthwise of the arm in response to the turning movement of the arm.

50 5. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and means to move the weight, in response to the turning movement of the arm, lengthwise of the arm first toward the pivotal axis thereof while traveling on one side of said axis, and thereafter away from said axis while traveling on the other side thereof.

6. In a winding machine, a member upwardly displaceable by accumulation of wound material, and counterweighting means for said member including: a pivoted arm, means to turn said arm on its pivot in response to the displacement of the member, a weight on the arm, and a cam to move the weight lengthwise of the arm in response to the turning movement of the arm.

7. In a winding machine, a member upwardly displaceable by accumulation of wound material, and counterweighting means for said member including: a pivoted arm, means to turn said arm on its pivot in response to the displacement of the member, a weight on the arm, and a cam to move the weight in opposite directions lengthwise of the arm in response to the turning movement of the arm.

8. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and a cam to move the weight lengthwise of the arm in response to the turning movement of the arm.

9. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and a cam to move the weight in opposite directions lengthwise of the arm in response to the turning movement of the arm.

10. In a winding machine, a member upwardly displaceable by accumulation of wound material, and counterweighting means for said member including: a pivoted arm, transmission means, actuated by the displacement of the member, to move the arm from a position at one side of its pivotal axis to a position at the other side thereof, a weight on the arm, and a cam to move the weight, in response to the turning movement of the arm, lengthwise of the arm first toward the pivotal axis thereof while traveling on one side of said axis, and thereafter away from said axis while traveling on the other side thereof.

11. In a winding machine, a member upwardly displaceable by accumulation of wound material, and counterweighting means for said member including: a pivoted arm, means to turn said arm on its pivot in response to the displacement of the member, a weight on the arm, means to move the weight lengthwise of the arm in response to the turning movement of the arm, and means to vary

the amplitude of the lengthwise movement of the weight.

12. In a winding machine, a member upwardly displaceable by accumulation of wound material, and counterweighting means for said member including: a pivoted arm, means to turn said arm on its pivot in response to the displacement of the member, a weight on the arm, a cam to move the weight lengthwise of the arm in response to the turning movement of the arm, and means to adjust the position of the cam to thereby vary the amplitude of the lengthwise movement of the weight.

13. In a winding machine, a member upwardly displaceable by accumulation of wound material, and counterweighting means for said member including: a sprocket, a flexible connection between the member and the sprocket, an arm to turn with the sprocket, a weight on the arm, and means to move the weight lengthwise of the arm in response to the turning movement of the arm.

14. In a winding machine, a member upwardly displaceable by accumulation of wound material, and counterweighting means for said member including: a sprocket, a flexible connection between the member and the sprocket, an arm to turn with the sprocket, a weight on the arm, and a cam to move the weight lengthwise of the arm in response to the turning movement of the arm.

15. In a winding machine, a member upwardly displaceable by accumulation of wound material, and counterweighting means for said member including: a sprocket, a flexible connection between the member and the sprocket, an arm to turn with the sprocket, a weight on the arm, and an arcuate cam to move the weight lengthwise of the arm in response to the turning movement of the arm.

Signed at the city of New York, in the borough of Brooklyn, county of Kings, and State of New York, this 8 day of October, 1928.

JAMES A. CAMERON.
